UNITED STATES PATENT OFFICE.

JOHN NELSON BANKS, OF MILAN, ITALY, ASSIGNOR TO MERGENTHALER LINOTYPE COMPANY, A CORPORATION OF NEW YORK.

TYPE OR MATRICES.

1,099,835.

Specification of Letters Patent.

Patented June 9, 1914.

Application filed February 18, 1913. Serial No. 749,071.

To all whom it may concern:

Be it known that I, JOHN NELSON BANKS, a subject of the King of Great Britain, residing at Milan, Italy, have invented certain new and useful Improvements in Type or Matrices, of which the following is a specification, reference being had therein to the accompanying drawing.

My invention relates to typographical machines, such as linotype machines of the general organization represented in Letters Patent of the United States, No. 436,532, to C. Mergenthaler, wherein circulating matrices are released from a magazine in the order 10 in which their characters are to appear in print, and then assembled in line, the composed line transferred to the face of the mold, the mold filled with molten metal to form a slug or linotype against the matrices 15 which produce the type characters thereon, and the matrices thereafter returned through a distributing mechanism to the magazine 20 from which they started.

More particularly it relates to the matrices employed therein, and to a special construction thereof whereby any character thereon may be made to appear at one or another alining level.

In the accompanying drawing, I have 25 shown my invention in preferred form and by way of example, and as applied to a linotype matrix, but obviously many variations and modifications may be made therein, and in its mode of application, and still be comprised within its spirit. Thus, in addition 30 to matrices having intaglio characters, it may be similarly adapted to types or dies having cameo characters and adapted for direct printing or indenting.

Generally speaking, I desire it to be understood that I do not limit myself to any specific form or embodiment, except in so far as such limitations are specified in the claims.

In the accompanying drawing: Figure 1 45 is an edge view of a plurality of my improved matrices assembled; Fig. 2 illustrates a special alinement thereof; and Fig. 3 is a side view of two of the matrices.

For purposes of illustration, I have shown 50 the matrices X as two-letter matrices, that is to say, as each formed with two intaglio characters Y, Y, in one edge. It will also be noted that the characters are in inverted position thereon. The matrices are provided 55 with the projecting ears A, whereby they

may be alined in the manner illustrated in the said Mergenthaler patent, namely, by moving them upward slightly just prior to the casting, so as to bring the ears A into firm contact with the under side of the mold, 60 the keeper-plate, or the like, and thus alining the characters along their tops, substantially as indicated in Fig. 1. My matrices are constructed with additional means whereby they may be alined in a different manner, such for instance as the notches B, formed in the upper ears thereof, and which are so located with reference to the characters Y that when suspended thereby, the characters are alined at their bases, as shown 65 in Fig. 2. The matrices X are also formed on their opposite edges with notches d and e, suitably located with reference to the characters Y and the supporting notches B, so as to register the latter with appropriate 70 supporting means, which are shown in Fig. 2 as consisting of the ribs D and E. The notches d and e and the supporting ribs D and E are two in number, corresponding to 75 that of the characters on the matrix. 80

The matrices may first be assembled in the usual manner, as indicated in Fig. 1, and are then transferred laterally to the position shown in Fig. 2. During this transfer, the deflecting blade C engages the presented 85 notches d or e, so as to raise or lower the respective matrices, and register the notches B therein with one or the other of the supporting ribs D and E. The mechanism for effecting this result may be substantially like 90 that indicated in another application for Letters Patent executed by me as of even date herewith.

It will be noted that in the position indicated in Fig. 2, the characters are alined 95 along their bases instead of along their tops, as in the practice above referred to. In other words, my improved matrices are constructed with a plurality of alining means, to permit the alinement of the characters in a corresponding plurality of positions; and in the preferred form illustrated, these different alining means are so arranged that in one instance the characters are alined at 100 their tops and in another at their bottoms. Obviously, this principle may be carried to any extent desired or feasible, and to any number of required positions.

Among the many advantages involved in 105 my invention is the capability of its adapta-

tion to ordinary matrices already in stock, so that notwithstanding differences in size and style, they may be made available and mixed for common alinement, by simply providing them with the additional alining means; and, moreover, in this manner the matrices may be alined individually with reference to each other, instead of simultaneously as in the manner previously described. 10 For instance, the initial letters "H" and "L" were not originally designed to appear on the same base line with the other characters, when the characters are alined at their tops, as indicated in Fig. 1, but by the adaptation 15 of my invention thereto, they are properly alined when supported by the notches B, as illustrated in Fig. 2.

It will, of course, be understood that in the different matrices, the notches d and e 20 and the notch B will be suitably located to correspond to the particular style and size of the characters.

As previously pointed out, two systems of alinement are used in this art, one wherein 25 the characters are alined along their tops, and the other wherein the characters are alined along their bottoms. It will be understood therefore that the use of the expressions "top alinement" and "base alinement" in the claims is intended to refer to 30 these different systems.

Having thus described my invention, its construction and mode of operation, what I claim and desire to secure by Letters Patent 35 of the United States is, as follows:

1. A type or matrix provided with means to aline any given character thereon either at its top or base.

2. A type or matrix having a character

designed for top alinement, and provided with means to adapt such character for base alinement. 40

3. A type or matrix provided with means to present a given character thereon in either top or base alinement. 45

4. A type or matrix having projecting ears to govern the top alinement of a given character, and provided with a notch to govern the base alinement of said character.

5. A type or matrix having ears to present a given character for top alinement, and formed with a notch to present such character for base alinement. 50

6. A type or matrix having a character designed for top alinement and formed with a notch to support the matrix with such character in base alinement. 55

7. A type or matrix having a character designed for top alinement, and formed with a notch to bring such character into base alinement, and with a further notch to support the matrix with its character in base alinement. 60

8. A series of type or matrices having characters of different sizes, and provided with means for bringing said characters into top or base alinement as desired. 65

9. A series of type or matrices having characters designed to be alined at one of their ends, and provided with means whereby the characters may be alined at their opposite ends. 70

In testimony whereof I affix my signature in presence of two witnesses.

JOHN NELSON BANKS.
